14 Claims. (Cl. 101—335)

1

This invention relates to potteryware decorating machines, and more particularly to the apparatus therein for inking decorating stamps.

Emerson Patent No. 2,437,224 discloses potteryware decorating apparatus in which decorating stamps are carried by the opposite ends of a horizontally oscillating crosshead. As the crosshead oscillates, first one stamp and then the other is positioned above an inking platen and then above the ware to be stamped. During pauses between oscillations the stamps are moved down to press one against the platen and the other against the ware. The "ink" is spread over the periodically rotated platen by means of a roller that rolls back and forth across the platen. The patented machine works very well when opaque ink, such as gold, is used. It has been found, however, that ceramic inks, which are glass-like when fired and therefore more or less translucent, are not spread out evenly enough on such a platen for consistently good decorating. The result is that the ink picked up by the stamp does not have uniform thickness, so when the decoration is fired the places where the decoration has been applied more heavily than others appear darker. This is undesirable when the entire decoration is supposed to be the same shade of color, as is the case with the well known "Blue Willow" patterns.

In an attempt to improve this situation, it was decided to spread the ink out evenly on the platen by means of a doctor blade traveling continuously around the axis of the platen. For a few revolutions of the blade this seemed to be the solution of the problem, but it was found that after that globules of ink started to form along the blade and then to leave its trailing edge and distribute themselves over the smooth surface of the thin layer of ink on the platen. These globules were picked up by the stamp and formed dark spots or smears in the decoration stamped on the ware.

It is among the objects of this invention to provide a potteryware decorating machine in which a thin layer of ink of uniform thickness is spread out on a platen by means of a doctor blade, and in which globules of ink adhering to the blade are periodically transferred from it to the ink on the platen in a location where they will not be picked up by the decorating stamp.

In accordance with this invention, a horizontal platen is provided with an ink-receiving surface, above which a doctor blade is mounted. The blade is spaced from the platen a distance

2

equal to the desired thickness of the ink that it spreads on the platen. Provision is made for moving the blade horizontally over the platen to spread ink out evenly on its surface. To remove adhering globules of ink from the blade it is raised periodically. This is done over an area of the platen where the globules, which are thus transferred from the blade to the platen, will not be picked up by the decorating stamp that receives ink from the platen. It is preferred that the ink-receiving surface of the platen be circular, and that the doctor blade extend across the space between the center of that surface and its circumference. In such a case the blade is driven continuously around the platen, and preferably is raised every time it reaches a certain point removed from the area where the stamp receives its ink. The outer end of the blade is advanced circumferentially of the platen relative to the inner end of the blade so as to maintain the roll of ink in front of the blade substantially uniform in size from end to end. This keeps the roll of ink from moving lengthwise off either end of the blade to any material extent. A desirable way of raising the blade periodically is by means of one or more cams. Although the rotating blade may be driven from either end, it is more satisfactory to drive it from its outer end, such as by a continuously rotating horizontal ring connected with the blade.

The preferred embodiment of the invention is illustrated in the accompanying drawings, in which Fig. 1 is a side view of our machine with the stamps raised; Figs. 2 and 3 are horizontal sections of the machine taken on the lines II—II and III—III, respectively, of Fig. 1; Fig. 4 is a cross section of the machine taken on the line IV—IV of Fig. 1; Fig. 5 is an enlarged fragmentary vertical section of the inking apparatus taken on the line V—V of Fig. 2; Fig. 6 is a view of the outer end of the inking arm; Fig. 7 is a vertical section through the arm taken on the line VII—VII of Fig. 5; and Fig. 8 is a reduced view, similar to Fig. 5, but with the doctor blade advanced about 90 degrees around the platen and raised by the cams.

Referring to Figs. 1 to 4 of the drawings, the table top 1 of a frame supports a vertical sleeve bearing 2 rigidly mounted on it. Extending through this bearing and the table is a hollow shaft 3 that is splined on a post 4 rotatably mounted near its lower end in a bearing 5. This bearing is mounted on a cross member 6 attached to a pair of spaced beams 7 and 8 extending

lengthwise of the frame about midway between its top and bottom. Rigidly mounted on the upper end of the hollow shaft is a crosshead forming a pair of arms 9 and 10 projecting in opposite directions from the shaft. The outer ends of the arms carry stamps 12 and 13 for decorating the upper surface of a dinner plate 14 or the like. When one of the stamps is made of such size that it decorates only the bottom of the plate while the other stamp is made larger for the purpose of stamping a design around the brim of the same plate, the larger stamp 13 is connected to its supporting arm in such a way that it can be flexed downward and outward to fit the inclination of the brim. Apparatus enabling this to be done is shown in the drawings but is not described here, because it forms no part of the present invention.

Disposed above the table at opposite sides of sleeve bearing 2 and directly below the two stamps are inking and ware-supporting members. The ware-supporting member includes a horizontal chuck 17 on which a flexible suction cup 18 is mounted. The centers of the cup and chuck are connected by a passage to the upper end of a vertical pipe 19 on which the chuck is rigidly mounted. The pipe extends down through table 1 and a tubular support 21 slidably mounted in bushing 22 mounted in the table. The lower end of the pipe is connected with a tube 23 that is connected through a valve 24 to a vacuum pump 25 at the opposite end of the machine. When the valve is open, the air pressure between the suction cup and dinner plate 14 is reduced so that the plate is drawn down tightly on the chuck and held there against displacement during stamping. The lower end of support 21 is connected through a post 26 to a roller 27 supported by a cam 28 mounted on a shaft 29. This shaft is journaled in bearings 31 mounted on vertical supports 32. Other details regarding the mounting for the chuck are not described herein, because they do not form a part of this invention.

Just before valve 24 is opened, the dinner plate is centered on the chuck by three vertical centering fingers 33 mounted on the ends of arms 34. The opposite ends of the arms are pivotally mounted on the upper ends of pins 36 secured to the top of the frame at equally spaced intervals around the chuck and at uniform distances from its axis. Rotatably mounted on each pin below the arm is a roller 37 that projects into a peripheral groove in a horizontal ring 38. The ring is rotatably supported by the rollers. The pivoted end of each arm has a bifurcated lateral projection 39 that straddles a pin 41 projecting from the top of the ring. It will thus be seen that if the ring is turned, the pin will swing the arms and cause the centering fingers either to engage and center a plate mounted on the chuck or to move away from the plate, depending upon which way the ring is turned.

For turning the ring, a pin 42 projecting from its bottom is engaged by the bifurcated end of an arm 43 rigidly mounted on the upper end of a shaft 44 that is journaled in table 1 and in a bearing 46 on beam 7 below it. The lower end of the shaft carries a laterally projecting arm 47 that is periodically swung back and forth by an actuating member. This member includes a rod 48 slidably mounted in bearings 49 and 50 mounted on beam 7. Slidably mounted on the rod adjacent bearing 49 is a sleeve 51 which is

urged to the right by a coil spring 52. The other end of the rod rides in a grooved cam 53 rigidly mounted on a horizontal cam shaft 54 journaled in bearings 55 supported by beams 7 and 8. Every time one of the cam notches reaches the adjoining end of the rod, the spring moves the rod toward the axis of the cam and thereby turns the shaft 44. If the plate is engaged by all three centering fingers before the rod stops moving, the plate is not broken, because the spring is not strong enough for that. Cam shaft 54 is driven continuously from an electric motor 61 mounted in the base of the frame. The motor is connected by a belt 62 to a pulley 63 mounted on one end of a shaft 64 journaled in bearings 66 in the bottom of the frame. The other end of the shaft supports a smaller pulley 67 which drives, through a belt 68, a pulley 69 above it connected to a speed reducing unit 70. This unit is mounted on a projecting end of the cam shaft 54.

In order to reciprocate the stamps so that they will engage the dinner plate and the inking member, a cylindrical bearing 75 is loosely mounted on the lower end of hollow shaft 3 between a pair of collars 76. Opposite sides of this bearing are recessed to provide parallel flat areas, against which blocks 71 are reciprocable transversely of the shaft. These blocks are pivotally connected by pins 78 to the forks of the bifurcated end of a lever 79. The opposite end of the lever is pivotally mounted on a horizontal shaft 81, while one side of its central portion carries a roller 82 that projects into a groove in the side of a cam disc 83 rigidly mounted on the cam shaft. Consequently, as the cam raises and lowers the lever, hollow shaft 3 is moved up and down on post 4 with which the shaft can rotate in sleeve bearing 2. When the shaft descends, axial alignment of the stamps with the ware on the chuck is assured by guide fingers 84 projecting downward from the cross head arms and which slide between rollers 86 at the outer end of a guide member 87 projecting laterally from the top of the sleeve bearing. Lateral movement of the stamps during stamping is thus prevented. Also, as the stamps descend, the suction valve 24 is opened by a cam 88 on a shaft 29 which is driven by a sprocket 89. The sprocket is driven by a chain 90 extending around another sprocket 91 on one end of cam shaft 54. The valve in the suction line is held open until after the stamp has risen away from the ware.

The side of cam disc 83 opposite to roller 82 is provided with another groove that contains a roller 93 connected to the side of a lever 94 which is pivotally mounted on the horizontal shaft 81 journaled in bearings 96 connected to the side of upright members 97 extending from the table down to beams 7 and 8. As the cam disc 83 rotates, the lever is raised and lowered. The outer end of the lever is pivotally connected by a vertical link 98 to the outer end of an arm 99 that thereby oscillates a shaft 101 journaled in pedestal bearings 102 in the bottom of the frame. This shaft carries a bevel gear 103 that meshes with a bevel pinion 104 on the lower end of post 4 whereby the post is turned when the shaft is rotated. The relation of the gear teeth to the pinion teeth is such that for each oscillation of the gear the post is turned 180 degrees.

The apparatus for inking the stamps includes a circular horizontal platen 106 supported above

the table by legs 107 (Fig. 5). The platen is encircled by an upstanding side wall 108 that keeps ink or color on the platen from running off its outer edge. Secured to the bottom of the platen near its outer edge is a ring 109 that has a flange 111 encircling its lower end. Disposed directly below this ring is the inner portion of a horizontal ring gear 112 which likewise is coaxial with the platen and is slidably supported for rotation by a ring 113 that rests on the top of table 1. For a purpose to be described later, the ring gear is driven continuously by a pinion 114 mounted on the upper end of a shaft 116 journaled in a bearing 117 mounted on the table. The shaft extends down through the top of the table and supports a bevel gear 118. This gear meshes with a vertical bevel gear 119 on one end of a horizontal shaft journaled in bearings 121 (Fig. 4) secured to the bottom of the table. The opposite end of this shaft carries a sprocket 122 that is driven by a chain 123 from a sprocket 124 on cam shaft 54.

The center of the platen is provided with an opening encircled by a cam ring 126 which also forms a wall for the inner edge of the platen. Extending through the opening is a post 127 which is rigidly mounted on the top of the table. A block 128 is rotatably and slidably mounted on the post above the cam ring. The block is supported by a cam follower roller 129 projecting from one side of it and resting on top of the cam ring. The block is pressed downward by a coil spring 131 encircling the post above it and compressed between the block and a nut 132 on the upper end of the post. This block supports the inner end of an arm 133 that extends outward across the platen and across its outer wall 108. The outer end of the arm has a downward extension, to the lower end of which a cam follower roller 134 is secured. This roller rides on flange 111 of platen ring 109 and thereby supports the outer end of the rod. As shown in Fig. 6, the outer end of arm 133 also has a rearwardly projecting lug 136 provided with a vertical opening through it for slidably receiving a post 137. The lower end of this post is rigidly mounted in ring gear 112, so that it is carried around the platen by the rotating gear. A coil spring 138 encircles the post between the lug and a nut 139 on the upper end of the post. It will be seen that with this arrangement the post 137 carries the arm around the platen and thereby rotates block 128 around center post 127. At the same time, however, the arm and block are free to be moved vertically on the two posts for a purpose that will be described presently.

A supply of ceramic color on the platen is spread out evenly over its upper surface by means of a doctor blade 141 that is carried around the platen continuously by means of arm 133. The blade may be connected to the arm in any suitable manner which permits it to be adjusted vertically. Preferably, the blade is provided with vertical slots 142, through which thumb screws 143 extend for clamping it against the front of the arm. To permit fine vertical adjustments of the blade to be made, the arm may be provided with a pair of longitudinally spaced vertical bores, the lower portions of which are cut out to form vertical slots 144 in the front face of the arm as shown in Fig. 7. Slidably mounted in these slots and bores are hook bolts 146, the lower ends of which extend through holes in the blade. The threaded upper ends of the hook bolts extend above the arm and are threaded in sleeves 147 that are mounted be-

tween brackets 148 connected to the front and back of integral bosses 149 on top of the arm. Threaded on the sleeves are nuts 151 and 152. When thumb screws 143 are loosened, the nuts can be turned to raise or lower the blade relative to the arm or to level the blade. Then the thumb screws can be tightened to hold the blade in the new position.

The doctor blade is set with its lower edge only 10 a slight distance above the platen so that it will spread the color out into a very thin layer or film. The blade is maintained parallel to the platen in order to make the layer of color uniform in thickness. The surplus color forms itself into a roll 15 extending the full length of the blade and that is rolled around the platen by the rotating blade. As the color is removed from the platen by the stamps, it is replenished from the roll, to which more color can be added from time to time. The arm 133 and blade are not disposed truly radially 20 of the platen, because that would cause the roll of color to travel lengthwise toward the outer end of the blade. Instead, as shown in Fig. 2, the outer end of the arm is advanced circumferentially of the platen relative to its inner end an amount 25 sufficient to keep the roll of color from moving endwise. This can be done by fastening the inner end of the arm to one side of block 128 in such position that the arm extends outward at an angle to a line perpendicular to that side of the block. An angle of about 10 degrees has been found to be satisfactory.

After the doctor blade has made a few revolutions around the platen, globules of color start 30 to form along the bottom of the blade. If the blade travels continuously in the same horizontal plane the globules will break away from the trailing edge of the blade and distribute themselves over the film of color on the platen. Those 35 that are deposited in the area where the stamps are inked will be picked up by the stamps and smear the decorations on the ware. It is a feature of this invention that the deposit of such globules of color on the platen is avoided in the area engaged by the stamps. This can be accomplished by raising the doctor blade periodically for a moment. It is most convenient to do this once every revolution by means of cams. Thus, the inner cam ring 126 is provided with 40 a raised cam 155, over which roller 129 must roll. When this happens, the roller raises the block on center post 127 and thereby elevates the arm and doctor blade momentarily. To help in this raising and to prevent sagging of the outer 45 end of the arm, the flanged ring 109 beneath the platen also is provided with a cam 156, over which the outer roller 134 rolls at the same time that the inner roller rolls over cam 155. The two cams therefore are disposed on opposite 50 sides of the center post. When the arm and block are raised by the cams, the springs on posts 127 and 137 are compressed and quickly 55 push the block and arm back down again as soon as the rollers leave the cams. The cams are located in a position where the arm will be raised soon after it has left the area of the platen where the stamps are inked.

It has been found that by periodically lifting 60 the doctor blade momentarily in this manner the globules of color which were formed on it while it was spreading the color out thin on the platen will be removed while the blade is passing over the mound of color that is formed on the platen where the blade is raised by the cams. Before 65 new globules are formed on the blade in suffi-

ent number to be deposited on the inking area of the platen; they are removed when the blade is raised the next time. The reason why or the manner in which the globules are removed from the doctor blade when it is lifted is not fully understood, but the fact remains that they are removed. One explanation is that as the blade approaches the mound of color between the two cams the blade pushes the mound ahead slightly, so that when the blade starts to descend from its elevated position it cuts down into the forward portion of the mound, which thus wipes the globules from the blade. In any event, when the blade leaves the mound of color it is substantially free of color globules and does not deposit any on the color in the inking area. Consequently, with this apparatus a smooth layer of color of uniform thickness always is spread out evenly over the inking area of the platen so that the stamps will pick up a uniform film of color and will stamp on the ware decorations that will be colored a uniform shade after firing.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. In a machine for stamping decorations on potteryware, a horizontal platen provided with a circular ink-receiving surface, a doctor blade extending across the space between the center and circumference of said surface a short distance above the platen, means for driving the blade continuously around the platen to spread ink out evenly on it, and means for raising the blade periodically to remove adhering globules of ink from it.

2. In a machine for stamping decorations on potteryware, a horizontal platen provided with a circular ink-receiving surface, a doctor blade extending across the space between the center and circumference of said surface a short distance above the platen, means for driving the blade continuously around the platen to spread ink out evenly on it, the blade being askew relative to the radius of said surface with the outer end of the blade in advance of its inner end, and means for raising the blade periodically to remove adhering globules of ink from it.

3. In a machine for stamping decorations on potteryware, a horizontal platen provided with a circular ink-receiving surface, a doctor blade extending across the space between the center and circumference of said surface a short distance above the platen, means for driving the blade continuously around the platen to spread ink out evenly on it, the outer end of the blade being advanced circumferentially of said surface relative to the inner end of the blade sufficiently to maintain in front of the blade a roll of ink of substantially uniform size from end to end, and means for raising the blade periodically to remove adhering globules of ink from it.

4. In a machine for stamping decorations on potteryware, a horizontal platen provided with a circular ink-receiving surface, a doctor blade extending across the space between the center and circumference of said surface a short distance above the platen, means for driving the blade continuously around the platen to spread ink out

evenly on it, and a cam for periodically raising the blade momentarily to transfer adhering globules of ink from it to a predetermined area of the ink on the platen.

5. In a machine for stamping decorations on potteryware, a horizontal platen provided with a circular ink-receiving surface, a doctor blade extending across the space between the center and circumference of said surface a short distance above the platen, a continuously rotating member connected with the outer end of the blade for carrying it around the platen to spread ink out evenly, and means for raising the blade periodically to remove adhering globules of ink from it.

6. In a machine for stamping decorations on potteryware, a horizontal platen provided with a circular ink-receiving surface, a doctor blade extending across the space between the center and circumference of said surface a short distance above the platen, a horizontal ring coaxial with said surface, means for rotating the ring continuously, means connecting the ring with the outer end of said blade to move the blade with the ring, and means for raising the blade periodically to remove adhering globules of ink from it.

7. In a machine for stamping decorations on potteryware, a horizontal platen, a post extending above the center of the platen, a support slidably and rotatably mounted on the post, a doctor blade connected with the support and extending outward toward the edge of the platen, means for rotating the blade continuously around the post to spread ink out evenly over the platen, and a cam for raising said support periodically to lift the blade so as to remove adhering globules of ink from it.

8. In a machine for stamping decorations on potteryware, a horizontal platen, a post extending above the center of the platen, a support slidably and rotatably mounted on the post, a doctor blade fastened to the support and extending outward toward the edge of the platen, means for rotating the blade continuously around the post to spread ink out evenly over the platen, a stationary cam, and a cam follower roller carried by said support and engageable with the cam for periodically raising the support to lift the blade.

9. In a machine for stamping decorations on potteryware, a horizontal platen, a post extending above the center of the platen, a support slidably and rotatably mounted on the post, an arm extending from the support outward across the platen, a doctor blade carried by the arm a short distance above the platen to spread ink evenly thereon, means connected with the outer end of the arm for rotating said support around the post, and a cam for periodically sliding the support up the post to lift the blade.

10. In a machine for stamping decorations on potteryware, a horizontal platen, a post extending above the center of the platen, a support slidably and rotatably mounted on the post, an arm extending from the support outward across the platen, a doctor blade carried by the arm a short distance above the platen to spread ink evenly thereon, means for adjusting the blade vertically on the arm, means for rotating said support around the post, a stationary cam, and a cam follower roller carried by said support and engageable with the cam for periodically raising the support to lift the blade momentarily.

11. In a machine for stamping decorations on potteryware, a horizontal platen, a post extend-

ing above the center of the platen, a support slidably and rotatably mounted on the post, an arm extending from the support outward across the platen, a doctor blade carried by the arm a short distance above the platen to spread ink evenly thereon, means for driving the arm continuously around the platen, and separate cams disposed adjacent said support and the outer end of the arm and simultaneously operable to lift the support and arm together periodically.

12. In a machine for stamping decorations on potteryware, a horizontal platen, a post extending above the center of the platen, a support slidably and rotatably mounted on the post, an arm extending from the support outward across the platen, a doctor blade carried by the arm a short distance above the platen to spread ink evenly thereon, a horizontal ring coaxial with said surface and located below the outer end of the arm, a vertically sliding connection between the ring and arm, means for rotating the ring continuously, and a cam for periodically raising the arm relative to the ring to lift the blade.

13. In a machine for stamping decorations on potteryware, a horizontal platen, a post extending above the center of the platen, a support slidably and rotatably mounted on the post, an arm extending from the support outward across the platen, a doctor blade carried by the arm a short distance above the platen to spread ink evenly thereon, a horizontal ring coaxial with said surface and located below the outer end of the arm, a vertically sliding connection between

25

the ring and arm, means for rotating the ring continuously, a stationary cam near the ring, and a cam follower roller carried by the outer end of the arm and engageable with said cam for periodically raising the arm to lift the blade.

14. In a machine for stamping decorations on potteryware, a horizontal platen, a post extending above the center of the platen, a support slidably and rotatably mounted on the post, an arm extending from the support outward across the platen, a doctor blade carried by the arm a short distance above the platen to spread ink evenly thereon, a horizontal ring coaxial with said surface and located below the outer end of the arm, a post projecting upward from the ring, the outer end of the arm being connected to the ring post for vertically sliding movement only, a roller carried by the outer end of the arm, a circular track supporting the roller, and means for raising said support periodically to lift the blade.
